UNITED STATES PATENT OFFICE.

HARRY DODGE, OF DANVERS, MASSACHUSETTS.

TREATMENT FOR HIDES AND SKINS.

No Drawing.

Application filed July 8, 1927. Serial No. 204,428.

This invention relates to the treatment of hides and skins, more particularly to the curing of the latter prior to the tanning thereof, and has for its object the curing, in a manner 5 as hereinafter set forth, of hides and skins to increase the quality thereof after tanning.

Hides and skins substance consists of animal flesh on one side and grain on the other side held together by fibers similar to fine 10 threads. These fibers are all inlaid in a gelatinous substance. The object in conditioning hides and skins for the purpose of being tanned into leather is to set this gelatinous substance more solid and at the same time 15 not allow it to run or be forced out, and it is the primary object of this invention to cure in a manner whereby more of this gelatinous substance will be held in the hide or skin than heretofore, so when cured the 20 hide or skin will have more substance, more gelatin, and more weight resulting when tanned into leather in a higher quality or rating in the market, than would be the case 25 if the hides and skins were cured in salt as in accordance with the method now generally used.

The hides and skins when cured, in accordance with this invention, are treated with a composition consisting of common salt, 30 nitre, either potassium nitrate or sodium nitrate, bicarbonate of soda and formaldehyde. The said several materials can be either used combined with water to form a bath for the 35 hides or skins or combined without water and applied to the flesh side of the hide or skin.

Preferably the method of curing hides and skins, in accordance with this invention, to 40 every 100 pounds of hides or skins, consists in placing into a receptacle a body of cold water of an amount capable of submerging the skins therein. Salt is then added to the water until a Twaddell No. 1 hydrometer will register from ten to thirty five. Then 45 there is dissolved from one eighth of a pound to three pounds of nitre, either potassium nitrate or nitre NaNO_3 , and which is added to the salt and water. After the adding of the nitre, there is dissolved from one-eighth of a 50 pound to two pounds of bicarbonate of soda and which is then added to the mixture in

the receptacle. After the bicarbonate of soda has been added to the mixture there is placed into the latter from one-eighth of a pound to one pound of formaldehyde. After 55 the solution or bath has been formed the hides or skins are placed therein. When the hides or skins have absorbed enough of the solution they are removed therefrom and stacked into piles and allowed to lay until 60 they have taken up all the solution possible by the pressing in piles and which probably will take from one week to six months to condition. The longer the time the skins or 65 hides are allowed to lay in wet packs the better they are conditioned.

When the skins taken from the animals are to be dried and shipped, they are submitted to the bath, in accordance with this invention before drying. When the skins 70 are to be kept in a wet state, they are allowed to cool for five or six hours in order for the animal heat to leave them, the several ingredients aforesaid are admixed together without water and are rubbed on the flesh 75 side of the hide, or the skins are placed in the bath as many times as desired. The number of times to which the skins are subjected to the solution or bath just depends on how long the hides or skins are to be kept 80 before being shipped or tanned into leather.

By treating the hides or skins in the manner as stated, the gelatinous substance is set in a more solid manner and at the same time not allowed to run out of the skins or hides whereby the hides or skins will hold more of this gelatinous substance while curing, also the skins will accept a greater per cent of salt, therefore, the skins when cured will have more substance, more gelatin, and more 90 weight and which will result, when tanned into leather, of a higher quality and higher rating, than would be the case if the same skins had been cured by the salt method now generally in use.

It is thought the many advantages derived from the treatment of hides and skins, in accordance with this invention, can be readily understood, and although the preferred embodiment of the invention is as illustrated 100 and described, yet it is to be understood that changes in the proportions of the sev-

2
eral ingrediants or substances can be had which will fall within the scope of the invention as claimed.

What I claim is:

1. In the curing of hides and skins the applying thereto of a composition including salt, nitre, bicarbonate of soda and formaldehyde.

2. In the curing of hides and skins, the subjecting them for a suitable period to a ¹⁰ bath consisting of water, salt, nitre, bicarbonate of soda and formaldehyde.

In testimony whereof, I affix my signature hereto.

HARRY DODGE.
